UNITED STATES PATENT OFFICE.

ERNEST ALBERT IVATTS, OF PARIS, FRANCE, ASSIGNOR TO SOCIETY COMPAGNIE GENERALE DE PHONOGRAPHES, CINEMATOGRAPHES ET APPAREILS DE PRECISION, OF PARIS, FRANCE.

CINEMATOGRAPHIC PROJECTING APPARATUS.

1,205,996.

Specification of Letters Patent.

Patented Nov. 28, 1916.

Application filed January 29, 1912. Serial No. 674,109.

To all whom it may concern:

Be it known that I, ERNEST ALBERT IVATTS, a citizen of Great Britain, residing at Paris, in the Department of the Seine, 5 and Republic of France, have invented certain new and useful Improvements in Cinematographic Projecting Apparatus, of which the following is a specification.

This invention relates to moving picture 10 projecting machines, and more particularly, to the kind in which electrical light and incandescent lamps are used, and the object of the invention is to provide a self-contained, safe and simple apparatus adapted 15 for use by persons not skilled in the art and at any place whether or not it has independent electrical current or any other appliances which were hitherto necessary for moving picture projections. These objects 20 are attained by the arrangement shown in the accompanying drawings, in which—

Figure 1 is a front view of the machine; Fig. 2, a side view of the same; and Fig. 3, a plan view showing the apparatus ready 25 for use.

In order to simplify the handling of the machine and reduce its dimensions and weight, all its parts have been reduced in size, number and weight and mounted on 30 the same framing supported by a common plate, which facilitates placing of the machine on any flat surface.

As may be seen from the drawings, the various parts have been located relatively 35 one to the other so as to make their coöperation easy and have all the parts coördinated and depending upon the main shaft and a toothed drum mounted thereon.

A base or plate 1 supports the frame 2, 40 which is preferably formed as an open casting. On the front of said frame are located the various optical parts and a convenient intermittent motion device and obturator preferably inclosed in case 3, in front of 45 which the focusing lens 4 is mounted.

5 denotes the film gate or passage in which the film is moved intermittently, as usual.

The condenser is located in the tubular part 6, and 7 denotes the tubular casing 50 inclosing an electric incandescent lamp. This casing-containing lamp is detachable to permit of the electric lamp being changed and adjusted, if and when desired.

In casing 8, placed on the upper side edge

of frame 2, are contained the necessary gearings for connecting the mechanical parts of the optical system to the main shaft. 55

Beneath the casing 3 is placed the electrical generator 9, fly-wheel 10 and a pulley 11 mounted on a speed regulating device 12. 60 These parts provide the necessary electrical energy to the machine and automatically control the mechanism producing the light in order to avoid excess of current which would result in the 65 destruction of the incandescent lamp; said parts are also driven by the main shaft.

Behind the above-described elements is a cover 13 through the center of which passes a shaft 14 to which are connected driving 70 means to work the machine, in this particular instance, a crank handle 15. A toothed drum 16 is also mounted on the main shaft and its object is to control the film, the upper surface of the drum feeding the film to 75 the film gate and the lower surface carrying the film back to the lower reel where it is automatically rewound. Steady roller guides 17 are placed above and below cover 13. Two movable roller guides 18, mounted on 80 movable spring latches 19, are mounted so as to enable easy adjustment of the film which is at the same time pressed against the feed drum, thus insuring a correct feeding, the film perforations being engaged in 85 the projections 20 of the feeding drum 16.

A guide 21 mounted on an adjustable arm 22 is used as a bridge for the passage of the film from the toothed drum to the film gate.

The rear part of the frame comprises two 90 reels 23 and 24 on their respective spindles 25 and 26, arranged preferably one above the other in vertical position in order to reduce the space and facilitate unwinding and rewinding. The spindle 26 is also provided 95 with a driving pulley 27 and coupling device 28. The wind-off reel 23 may be rotated by hand by means of a gear wheel 29 having internal teeth, mounted on a spindle 30 and driving a cog wheel 31, keyed to the 100 spindle 25 of the wind-off spool 23. By a suitable manipulation of the clutch device 28, the shaft 26 may be made to turn freely in either direction, thus permitting the film to be rewound on to the reel 23 from the 105 reel 24, without being carried back through the projecting portion of the device.

As may be seen from the drawings, the

5 main shaft 14 and toothed drum 16 are located at the center of the apparatus and thus have the control of all the elements and parts of the machine so that by rotating said shaft 14, all the parts of the machine immediately start working in coördination, and when shaft 14 is slackened or stopped, all the parts of the machine at the same time slacken or stop.

10 The central part of the frame comprises a bearing 32, in which, and in cover 13, the shaft 14 is journaled. Shaft 14 carries a bevel wheel 33 which meshes with bevel wheel 34 on the end of shaft 35, the latter 15 driving the intermittent motion device and obturator. A cog wheel 36 drives cog 37 connected to the fly-wheel 38, the latter actuating pulley 11 of the generator 9 by a transmission 39, a pulley 40 communicating 20 movement by means of transmission 41 to the pulley 27 of the wind-on spool 24. Parts 33, 34, 36 and 40 are protected by a cover 42 mounted on the projecting part of the frame forming the bearing 32 of the drive shaft 14. 25 Having thus described my invention, what I claim as new and desire to secure by Letters Patent, is:—

eters apart, as:

1. In a moving picture projecting machine, the combination of a supporting base, a main driving shaft supported approximately centrally over said base, an optical system supported adjacent one end of said base, a wind-off reel and a wind-on reel supported in vertical alinement adjacent the opposite end of said base, a separate shaft for each reel, a film-feeding drum carried by said driving shaft and adapted to feed a film through the apparatus, a driving connection from the driving shaft to the wind-on reel, means for releasing said driving connection, and means for operating said wind-off reel independently of said driving shaft whereby a film may be wound directly from the wind-on reel to the wind-off reel.
2. In a moving picture projecting machine, the combination of a supporting base, a main driving shaft supported approxi-

mately centrally over said base, a film-feeding drum on said driving shaft, an optical system supported adjacent one end of said base at one side of the driving shaft a wind-off reel and a wind-on reel supported in vertical alinement adjacent the opposite end of said base and at the opposite side of the driving shaft, a separate shaft for each reel, a belt-drive connection between the main driving shaft and the shaft of the wind-on reel, clutch mechanism for releasing said belt-drive connection, and means for operating said wind-off reel independently of said driving shaft whereby a film may be wound directly from the wind-on reel to the wind-off reel without passing through said optical system.

3. In a moving picture projecting machine, the combination of a supporting base, a main driving shaft supported approximately centrally over said base, a film-feeding drum on said driving shaft, an optical system supported adjacent one end of said base at one side of the driving shaft, a wind-off reel and a wind-on reel supported in vertical alinement adjacent the opposite end of said base and at the opposite side of the driving shaft, a separate shaft for each reel, a belt-drive connection between the main driving shaft and the shaft of the wind-on reel, clutch mechanism for releasing said belt-drive connection, and means for operating said wind-off reel independently of said driving shaft whereby a film may be wound directly from the wind-on reel to the wind-off reel without passing through said optical system, said means comprising a gear secured to the spindle of the wind-off reel, an internally toothed wheel adapted to actuate said gear, and an operating handle rotating with said wheel. 65
